UNITED STATES PATENT OFFICE.

JEROME KIDDER, OF NEW YORK, N. Y.

IMPROVEMENT IN ELECTRODE-HANDLES FOR MEDICAL USES.

Specification forming part of Letters Patent No. **147,650**, dated February 17, 1874; application filed May 17, 1873.

To all whom it may concern:

Be it known that I, JEROME KIDDER, of New York city, in the county and State of New York, have invented a new and Improved Double Electrode for application to various parts of the body, of which the following is a specification:

The object of my invention is to provide for electro-medical purposes an improved double electrode for facilitating the adjustment of the amount of surface required, and the convenience of manipulating the current. My invention consists of a double electrode so constructed that both poles of the electric current can be brought to it, and still be insulated from each other, so that one pole of the current will be received in the hand that holds the electrode, while the other pole may be applied to other parts of the body, thus using the same with one hand, leaving the other free for other purposes.

The accompanying drawing represents a side elevation of my improved electrode, partly in section, in which—

A represents the cylindrical core, of hard wood, rubber, or other insulating material, which is perforated centrally throughout its whole length. The metallic wire rod B passes through core A, being threaded at one end, so that the socket a of set-screw b can be screwed over it. The perforation of core A is suitably widened to allow socket a to turn therein. A shoulder, d, of core A, at its opposite end, is made concave, to fit over the convex circular plate C, placed loosely on rod B. It is at the top of the hollow metallic plate or knob D, which is soldered, riveted, or otherwise connected to the end of rod B, and serves to clasp between knob

D and plate C the sponge or other material by which the electrical current is distributed over a larger surface. By tightening the socket a on the upper end of rod B, shoulder d presses plate C on the rim of knob D, holding the distributing material tightly between them. It may also be used without it, and be then applied to various parts of the body, concentrating the force of the current to those parts of the surface of plate D which are brought in contact with the body. The metallic tube E is placed around the core A, resting on shoulder d, being entirely insulated from the inner rod B. The set-screw b' at the upper end of tube F connects with the other pole of the battery. Both the incoming and outgoing currents are conducted through the electrode, so that the same may be applied by the use of one hand to those parts of the body requiring electro-medical treatment. Should the current be too strong for the hand, another electrode for the other hand may be thrown into the circuit by connecting the same with set-screw b', and by such distribution the effect of the current from that pole may be distributed to a greater degree, making it thus more bearable.

Having thus described my invention, what I claim as new, and desire to secure by Letters Patent, is—

The double electrode for applying electricity to various parts of the body, consisting of insulated core A, rod B, and outer metallic tube E, substantially as and for the purpose described.

JEROME KIDDER, M. D.
